POWDER FEEDER FOR A FLAME SPRAY GUN

Walter A. Siebein, Smithtown, N.Y., assignor to Metco,
Inc., Long Island, N.Y., a corporation of New Jersey

Filed Mar. 28, 1962, Ser. No. 69,463

Term of patent 14 years

(Cl. D55—1)

FIG. 1

FIG. 2

FIG. 1

FIG. 2

FIG. 1 is a front elevational view of a powder feeder showing my new design;

FIG. 2 is a side elevational view thereof, the other side being substantially a mirror image thereof;

FIG. 3 is a rear elevational view thereof; and

FIG. 4 is a top plan view thereof.

I claim:

The ornamental design for a powder feeder for a flame spray gun, as shown and described.
